(57) **CLAIM**

I claim the ornamental design for a cookie, as shown and described.

DESCRIPTION

FIG. 1 is a perspective view of a cookie, showing my new design;

FIG. 2 is a top plan view thereof;

FIG. 3 is a bottom plan view thereof;

FIG. 4 is a left-side elevational view thereof, the right-side elevational view being a mirror image thereof; and,

FIG. 5 is a front elevational view thereof, the rear elevational view being a mirror image thereof.

The broken lines showing a logo in FIGS. 1–3 depict environmental matter and form no part of the claimed design.
